cont'd.

UNITED STATES PATENT OFFICE.

JOSEPH A. CONTOIS, OF NEW BRITAIN, CONNECTICUT.

BLOCK-SIGNAL PROTECTIVE DEVICE.

Application filed August 15, 1923. Serial No. 657,607.

To all whom it may concern:

Be it known that I, JOSEPH A. CONTOIS, a citizen of the United States, residing at New Britain, in the county of Hartford and State 5 of Connecticut, have invented certain new and useful Improvements in Block-Signal Protective Devices, of which the following is a specification.

My invention relates to improvements in 10 block signal protective devices for use in connection with a block signal system on railroads and for the purpose of preventing the entry of a locomotive into a particular block after the signal has been set against the 15 same, and the object of my improvement is to provide means that are operative in co-operation with the air brake system to automatically effect the stopping of the locomotive after passing such a signal that is set 20 against the same, and which means comprise power driven control mechanism for effecting a graduate reduction of speed up to the full stop and thus avoiding a relatively quick and sudden complete stoppage and the violent and unpleasant sensations and possible 25 material damage consequent upon such quick action.

In the accompanying drawing:—

Figure 1 is an elevational and essentially 30 diagrammatic view of my improved block signal protective device in the set position and with the parts in position for being tripped, a part of the cab structure of the locomotive being shown.

Figure 2 is a similar view of the tripping 35 device and adjacent parts in the position immediately after being tripped.

Figure 3 is a plan view of the tripping lever, being on an enlarged scale.

Figure 4 is a plan view of the cam for effecting the setting of the handle for the air valve of the air brake system, the shaft being shown in section.

My improved block signal protective device 45 comprises a semaphore signal structure 10 that is constructed and arranged in part so as to operate like semaphore signals that are in common use and that has also incorporated in its structure a tripping device 50 that is adapted to cooperate with tripping mechanism on the locomotive for effecting the starting of a motor 11. The operation of said motor 11 serves to open a cock 12 that itself is incorporated in a pipe or con-

duit 13 that is part of the system for controlling the air-brakes. 55

The motor 11, as shown, is an electric motor that is supplied with current by means of the leads 29 and the motor shaft is operatively connected by means of gearing 15 60 with a countershaft 16, the gearing operating to effect a suitable reduction in speed.

Mounted on the counter-shaft 16 is a cam 17 that cooperates with a radial handle 18 on the plug member of the cock 12 for effecting the positioning thereof so as to open the 65 said cock 12 and thereby operate the air brake system.

The cam 17 is a plate-like form with the contact portion at the peripheral edge and 70 the details thereof are adapted to operate so that beginning with the cock 12 in the closed position an appreciable angular movement at the beginning of rotation will serve only to effect a gradual opening of the cock to the 75 substantially half-open position. Then for a short movement there will be a riding effect, involving no change in the position of the cock, and this will be followed by what may be termed the peak, involving full opening. 80 Between the peak and the starting position the cam is shaped so as to provide a guiding effect for permitting the fully closing of the cock.

Considering the cam 17 in detail, it is 85 mounted on the counter-shaft 16 by means of the opening 20, and is keyed thereon.

The peripheral bearing edge is provided with a slight indentation 21 which corresponds to the initial position, with the cock 90 12 fully closed. To one side of the starting indentation 21 and for approximately a quarter-turn is a zone 22 involving a gradual rise for effecting the half-opening of the cock. Next comes the riding zone 23, involving no 95 change, and this is followed by the point-like peak 24 for effecting the full-opening, and which may correspond to approximately a two-thirds turning movement. The return zone 25 is intermediate the peak 24 and the 100 starting recess 21.

The motor starting means may be, as shown, in the form of an electric-switch 26 that has a moving member 27 that operates by a reciprocating movement and is preferably positioned so as to be operated vertically and with the closing of the electric circuit as represented by the mains 28 and the motor 105

leads 29 corresponding to the downward or lowermost position thereof.

The moving member 27 is thus adapted to be attached to the lower end of a rod 30 that is supported for vertical sliding movement in any proper manner, as by means of guide-blocks 31. A coil spring 32 tends to thrust the rod 30 downwardly to the circuit-closing position.

10 The rod 30 projects upwardly through the roof 33 of the cab of the locomotive and has at its upper end a short laterally-directed overhanging branch 34 that serves as the tripping-nose arm, the latter being provided 15 on its lower face with a downwardly projecting stub or pin 35 that operates as the tripping nose.

10 The semaphore structure 10 comprises a post 36 that serves to operatively support a 20 swinging arm structure 37 through the medium of a pivotal pin 38, said arm carrying a display device 39 of any usual and approved form. A counter-weight 40 may be provided on the rear or outer end portion 41 of the 25 swinging arm structure 37 and at the inner side of the post 36 there may be provided a bracket-like guide structure 42. Adjacent the free end portion 43 of the swinging arm structure 37 is a pendant branch 44 and intermediate 30 said free end portion 43 and the body portion is a connecting intermediate part 45 that serves to position the pendant branch appreciably below the elevation of the pivotal pin 38 of the semaphore structure 35 10.

Said pendant branch 44 serves as a tripping arm and in the position for use hangs downwardly in some part of the space immediately over some part of the locomotive 40 as it travels along the rails and is positioned in the path of a cooperating arm 46 that is supported by the locomotive.

Said cooperating arm 46 is part of a swinging member 47 that is supported for 45 swinging to a limited extent back and forth in a horizontal plane.

Said swinging member 47 operates as an intermediate member between the pendant arm 44 and the nose 35.

50 As shown, said swinging or intermediate member 47 is operatively supported on a platform 48 by means of a pivotal pin 49, the cooperating arm 46 being on one side of the pivot 49 and the arm 50 on the opposite side thereof serving to cooperate with the nose 35. Springs 51 of any suitable form serve to generally position the swinging member 47.

More positive means for positioning the 60 swinging member 47, particularly under the set condition, previous to the tripping, are provided in the means for cooperating with the nose 35 and which comprise simply a depression or notch 52 that serves as seat 65 for receiving and also generally guiding the

said nose 35 and the branch arm 34 by which it is supported.

The holding effect on the nose 35, as described, is simply in the form of a frictional hold that is adapted to be released 70 responsive to a relatively forcible movement of the swinging member 47 such as follows the contacting of the cooperating arm 46 with the pendant arm 44.

When the nose is tripped in the manner 75 described the rod 30 is dropped by the spring 32 and the electric switch 26 is closed, resulting in starting the motor. The latter then moves the cam 17 so that the air-cock 12 is operated so as to set the brakes, the 80 latter operation being controlled so as to avoid instantaneous operation of the brakes.

A stop-pin 52 in the bracket-structure 42 serves to limit the downward movement of the swinging arm structure 37 to the proper 85 position for permitting the pendant branch 44 thereof to cooperate with the laterally directed cooperating arm portion 46 of the swinging member 47 in the manner described.

90 Various changes may be made from the particular arrangement shown and described. Thus in some cases an air motor may be used instead of the electric motor, the air supply therefor being taken from 95 the same source as that for the brakes.

I claim as my invention:—

1. A block signal protective device comprising in combination a semaphore signal structure having a signal arm that is adapted 100 to overhang the path of a locomotive and has a pendant tripping arm, the locomotive being provided with an air-brake system having a control-cock, tripping mechanism on the locomotive for cooperating with said pendant tripping arm, a motor and control means therefor operated by said tripping mechanism, and means for operating said cock operated by said motor, said last named means comprising a cam device for effecting 105 a graduated movement in operating said cock, said tripping mechanism comprising an electric switch and a horizontally positioned swinging member, said swinging member having an arm for cooperating with 110 said pendant tripping arm, a vertically reciprocating rod structure serving as means for operating said switch and having spring means tending to effect a downward movement of said rod structure, and said swinging member having a second arm for cooperating with said rod structure to hold the same in elevated position in opposition to said spring means.

2. In a block signal protective device for 115 use with a locomotive having an air brake and with a semaphore structure, a motor for operating said brake, a vertically reciprocating motor control device, a swinging member pivotally supported by said 120

comotive and having oppositely directed arms, one of said arms cooperating with said semaphore structure for effecting a lateral movement of said swinging member, said motor control device having a branch for cooperating with the other of said arms for providing normal supporting means for said

motor control device, and means for dropping said motor control device responsive to such lateral movement of the swinging member, involving disengagement of said branch from the cooperating arm.

JOSEPH A. CONTOIS.
